UNITED STATES PATENT OFFICE.

JOHN F. MULLANEY, OF COLORADO SPRINGS, COLORADO.

DOOR-CHECK.

1,143,773.

Specification of Letters Patent. Patented June 22, 1915.

Application filed August 12, 1909. Serial No. 512,586.

To all whom it may concern:

Be it known that I, JOHN F. MULLANEY, a citizen of the United States, residing at 741 East Cache La Poudre street, in the city of 5 Colorado Springs, in the county of El Paso and State of Colorado, have invented certain new and useful Improvements in Door-Checks, of which the following is a specification.

10 My invention relates to improvements in holders, for doors, gates, shutters and windows, in which a broad flat spring is fastened at both ends upon a door, gate, shutter or window, near the swing edge of 15 same or on some moving part thereof, and the central or curved part of the spring is adjustably made to press against the floor, under the door, or against some permanent immovable fixture, near the door, or other 20 aperture closing appliance, so as to cause a friction thereon to retard the movement of the door, or stop its movement entirely by means of friction or locking screws as desired; and the objects of my invention are: 25 first, to prevent a door from slamming abruptly; second, to prevent a door or window from moving from a desired position; third, to prevent noise of the door when closing it; fourth, to prevent a door or window from 30 making a rattling noise when influenced by the wind or other power; fifth, to hold the door, gate, window, or other aperture closing appliance, rigidly or adjustably, in any desired position, when closed, partially opened 35 or entirely opened; sixth, to hold the gate or door open adjustably at any desired position and have it movable, without digging the floor or ground under the gate or tearing the carpet on the floor under the door, and to provide 40 an automatic release of the door holder. I attain these objects by the mechanism and appliances illustrated in the accompanying drawings, in which:

Figure 1, is a side elevation of the edge 45 of a door with proper parts of the holder shown attached thereto; Fig. 2, is a side elevation of the spring B, loosed and in its normal shape, with dotted lines showing the bottom of the swing edge of a door, and the 50 position to be assumed by the arm 3, when put into place; Fig. 3, is a side elevation of the holder, attached to the lower swing edge of a door, and in position compressed down against the floor carpet, 16 and 16, and en-

gaging one of the locking screws 33; Fig. 4, 55 is an inside or rear elevation of the holder, on the inside of the door A, showing the spring B, released and up into the casing 8; Fig. 5, is an edge view of the casing 8, with its face plate 9, disconnected from all other 60 parts, and in the relative position as shown in Fig. 3; Fig. 6, is a flat side elevation of the arm 3, of the spring B, the staple 12, and tension nail 30, with part of the spring B, removed at the crimp 5, and showing the 65 teeth 18, 18, in arm 3; Fig. 7, is a side view of staple 12, and tension nail 30, showing a cross sectional view of the arm 3, of spring B; Fig. 8, is a side elevation of the holder, and of its parts attached to the lower swing 70 edge of the door A, and showing carpet 16; with the spring B, engaging one of the locking screws 33; Fig. 9, is a side elevation of the holder and the swing edge of door A, showing the bottom part 2, of spring B, of 75 the holder compressed upwardly, between the lower edge of door A, and the threshold 22, when the door is closed; Fig. 10, shows the arm 3, of the spring B, of the holder, in use without the casing 8, on the lower end 80 of the swing edge of the door; with the bottom curve 2, of the spring B, placed near the swing wall, and past the retention block 26, but not low enough to engage the locking 85 screw 33; Fig. 11, is a top view of a part of bottom curve 2, of spring B, showing slot-shaped hole 32, made to engage the head of one of the locking screws 33; Figs. 1, 2, 3, 4, represent the principal parts of the spring B, of the holder. 90

A, is the lower end of the swing edge of the door.

Similar letters and figures refer to similar parts throughout the several views.

The spring B, is a broad flat elastic spring 95 (usually of metal), which may be in width from one half inch to two inches or more, and its aggregate length may vary from three inches to twenty inches, or more, and may vary proportionally in thickness from 10 one eightieth of an inch to one eighth of an inch or more, depending upon the size of the door or gate, and the resistance to be overcome. The spring B, is fastened rigidly to the front of the door by means of nails, 105 screws, or clamps, as desired, and at the back is adjustably attached by means of staple 12, and of the tension nail 30, engag-

ing notches in the arm 3, which is the terminal arm of the spring B. This arm 3, is guarded from the contents of the room or from passers by, by means of the guard 8, 5 and its base plate 9. When the spring B, is released from the tension nail 30, the bottom curve 2, will rise up against the under edge of the door A, by reason of assuming its normal shape, so that the bottom curve 2 will 10 clear above the floor. In this position the door can be swung open and shut without interference with the floor, as though the holder were not on the door.

When it is desired to keep the door from 15 slamming, the operator presses his foot upon the step crimp 5, and forces it down, thus forcing down the bottom curve 2, against the floor to the desired tension, and thus maintains the pressure by forcing the teeth 20 in the rack in arm 3, against the side of tension nail 30, until one of the rack teeth 18, engages the tension nail 30, where it will be rigidly held by the upward pressure of 25 the bottom curve 2. The side motion of the foot on the step curve 4, will engage or release the teeth 18, 18, as desired.

To cause the door to be held rigidly, partly opened, the step crimp 5, is pressed down very forcibly by the foot or otherwise, 30 to the position as shown in Fig. 3, and locked in that position by forcing one of the rack teeth 18, to engage the tension nail 30, or it may be locked more rigidly to any position by inserting one of the locking screws 33, 35 in the path of the bottom curve 2, so as to engage the slot-shaped hole 32, which is situated longitudinally in the lowest part of the bottom curve 2 so that the head of the screw 33, will project through the hole 32.

40 The rack guard 8, and its base plate 9, serve as a guard to protect the arm 3, from coming into contact with the clothing of a person or with anything in the room, or with the finished body of the door A. The convolutions at 6, 7, and 20, serve the purpose 45 of more length of spring in a condensed form, and for more rounded form, to avoid contact with passing objects. The step crimp 5, is so sharply formed by the spring 50 B, being bent doubly upon itself, that it may be forced clear down to the floor without breaking, and is rounded, so as to be free from catching upon passing objects.

When the door is closed over the threshold 55 22, as shown in Fig. 9, the bottom curve 2, of the spring B, is forced up against the under edge of the door A, either by being released from the tension nail 30, or by coming 60 into contact with the threshold plate 23, which threshold plate is to prevent wear on the threshold and is held in place by nails 24, and 25, or by screws or other suitable means. The lower front crimp 7, is situated at a reasonable distance above the 65 level of the top of the threshold 22, so that

it will slide over the threshold or over a carpet or over a mat, or other obstruction upon the floor, without shoving it, or rolling it up, and when used under a gate or other swinging door, it will slide over obstructions 70 on the floor or ground, and will keep the gate in the desired position and will support the swing end of a wide gate. The step crimp 5, of spring B, is arranged so far above the floor that it will pass over the carpet or mat 75 or other obstruction on the floor without shoving it.

Fig. 10, shows the door A, shoved back nearly against the swing wall 29, and shows the retention block 26, fastened to the floor 80 on the line traversed by the bottom curve 2, of spring B, so that when the bottom curve 2, is held down against the carpet by means of the teeth 18, 18, of arm 3, engaging 85 with tension nail 30, by means of notches 19, 19, it may pass over retention block 26, by great force being applied, but when resting between said retention block 26, and the swing wall 29, it will remain there until removed by some greater force than a common wind, or than the power of a child. This holder is intended to be serviceable in preventing small children from shutting the door on their fingers, or the fingers of a playmate, and for preventing the door from 95 slamming and breaking the glass, or making a noise, etc., and for preventing doors in railway cars from moving, and windows from sliding up or down when not desired. One or more holders may be used on one 100 door and on different parts of the door as desired. With other holders of which I am acquainted, there is this distinction; the door can not be slid without tearing the carpet when the holder is in contact with the floor, 105 while this holder, no matter how rigidly held down, will slide over the carpet or mat, by the application of sufficient force and without tearing it, and the door with this holder, can be closed, by great force, sliding 110 the bottom curve 2, up over the threshold 22, and without breaking the holder, unless engaging one of the locking screws 33, which may project about one eighth ($\frac{1}{8}$) of an inch above the floor and can be screwed down 115 out of reach of the spring B, when desired, or covered with a mat or cloth, so that it will not be engaged.

The surface or face of the door check is of smooth hard material, as hardened steel, 120 and will not retain particles of grit or dust that might scratch or wear a smooth floor or carpet, but the dust or grit will be held on the floor or carpet and will not be shoved or slid on the floor or carpet and so will tend 125 to scratch or wear the surface of the door check instead of the floor or carpet as the dust will slide on the hard smooth surface and be pressed into a softer or rougher surface.

The rack guard 8, and its base plate 9, are fastened at the top, through crimp 10, by means of screws or of nails 11, and at the bottom of the base plate 9, it is held against the door by means of the shoulders on the two points of staple 12, passing through the edges thereof, near the lower end, and by means of lower crimp 15, of guard 8, passing up over the top of the head of said staple 12, and by means of tension nail 30, passing through the guard 8, and its base plate 9, leaving a free open channel between the guard 8, and its base plate 9, for the passage of arm 3, of the spring B.

15 The holder can be successfully used by attaching it to the swing edge of a door or gate so as to engage the door post or gate post, instead of engaging the floor, or the ground as is often the case, under the end 20 of a wide gate, and can be made to engage any suitable permanent fixture instead of the floor. A block may be attached to the inside of a window sash and the holder attached to the upper and lower edges of the 25 block, in such a manner that the bottom curve 2, will engage the jamb of the window frame. The same manner of appliance is used on a rising and falling door or shutter, or one that moves vertically, like a port-cullis. The door check in such cases may 30 be used for the purposes of adding only sufficient friction as is necessary to overcome the difference between the weight of the window or door and the weight of its 35 counterweights, or it may have the locking pins 33, to secure the door or window rigidly at some desired position or positions, or for both such purposes.

In doors not needing the protection of the 40 guard 8, it may be omitted and the staple 12, may also be omitted, and only the tension nail 30, used to attach the arm 3, to the inside of the door. In this condition, the arm 3, is retained from slipping off over the tension nail 30, by reason of the long T-head 45 17, on the tension nail 30, Fig. 7. If desired, a nail with a broad flat head, of any desired shape, may be used instead of a nail with a T-shaped head, for the purposes of the tension nail 30.

The arm 3, is stiffened by means of the raised ribs 35, and 36, shown in Fig. 6, and Fig. 7. The top or end of the arm 3, is bent outwardly as shown in Fig. 10, at 34, so as 55 not to dig into the door A, or other surface with which it may come into contact, and to stiffen it. The tension nail 30, may also be provided with a screw point, when preferred to a common driving nail point, 60 where the screw is preferable so as to turn the head 17, so as to adjust it to the desired distance from the door A. When desired, the bottom curve 2, may be made thicker at the wearing and friction surface than the 65 rest of the spring B.

I claim:—

1. A broad flat member of elastic material permanently bent upon itself so as to have its ends close together and attached to opposite faces of a door or gate near the swing 70 edge thereof, one of its ends being secured thereto rigidly and the other end being adjustably secured to the opposite face of said door or gate, the part of said member intermediate its ends being formed into a projecting curve extending around and free from the swing edge of said door or gate, and adapted to engage some fixture while said door is open, as a floor, for the purpose of arresting the motion of said door or gate. 75

2. In a door check, a spring in a horse-shoe shape, rigidly attached to a door, or other aperture-closing appliance, at one end by an attaching arm, and adjustably attached to said door, or other aperture-closing appliance, at its opposite end, by means of teeth in the adjustable arm, engaging a pin in said door, the curved-shaped form of the said spring being adapted to engage some fixture to arrest the motion of the said door, or other aperture-closing appliance, substantially as set forth and for the purposes specified. 90

3. In a door check, of the class described, a spring, having one of its ends secured rigidly to the face of a door or window sash, and having convolutions near said end, and having in its opposite end an elongated slot with rack teeth in one side adapted to engage a rigid pin projecting from the opposite face of said door or window sash, a convex slot-shaped hole, stiffening inturned ribs, on either side of said slot-shaped hole, in combination with a locking screw, permanently secured to some fixture, in the path of the slot-shaped hole, and provided to engage same, all substantially as set forth. 95

4. In a door check, of the class described, a door, a flat spring member having one end rigidly secured near the swing edge of the door, and being bent upon itself so that its connecting curve projects from and embraces one edge of said door, and having its opposite end attached to said door adjustably by means of teeth in a longitudinally 110 arranged slot in said spring near its end, in combination with a nail with a T shaped head, said head adapted to prevent said flat spring from slipping over said nail, said nail passing through said slot into said door 115 in a manner to engage said teeth, said connecting spring having a hole in the portion farthest projecting from the said door, adapted to engage a locking screw projecting from the floor in the path of the spring, a projecting obstruction attached rigidly to the floor or other stationary structure in the path of said connecting curve, to engage same to retard its passage but not projecting enough to engage the said door, in com- 120 125 130

bination with a housing inclosing the adjustable end of said spring, all substantially as set forth.

5. In a door check, the combination of a flat spring member, one end of which is permanently secured to one face of the door near a swing edge thereof, the opposite end of said spring having an elongated slot, the said slot being provided with rack teeth
10 adapted to engage a pin in said door to adjustably attach said spring to said pin, the part of said spring intermediate its ends being bent around said swing edge of the door and projecting therefrom so that it may project yieldingly against some fixture to arrest said door, while open, said spring being so formed normally as to withdraw from said fixture and hug the swing edge of the door when released from said pin, a protecting
15 shield covering the adjustable end of said spring, a hole in the curved part of said spring provided to receive the end of a locking pin projecting from said fixture, and adapted to arrest the motion of said spring,
20 25 a projecting corrugation extending outwardly at right angles to the plane line of the adjustable end of said spring adapted to be engaged by the human foot or hand to adjust said spring with said rack teeth and
30 35 said pin as provided, substantially as set forth and for the purposes specified.

6. As an article of manufacture, a long flat member of spring material bent into the form of an irregular bow, having a short arm, perforated with holes, adapted to receive nails to fasten it rigidly to the face of some aperture-closing appliance, and having the other extremity or long arm of said bow straight, being connected with the former said arm by the connecting convex curve of said bow, and while in its normal shape, the long arm extending inclined toward the extended line of the short arm, said long arm having a longitudinal slot
40 45 provided on one edge with rack teeth tending toward its end, and the connected part of the said long arm having a concave curve connection about one half the length of the long arm and extending outwardly at about right angles to the line of the said long arm and forming an acute crimp at its outer end with the outer end of the bow or main connecting curve and adapted to be engaged by the human foot, the center of the said
50 55 main connecting curve being provided with a slot-shaped hole extending longitudinally and adapted to receive the end of a pin, and with inward projecting ribs on either side of said hole, adapted to stiffen the spring, all substantially as set forth.

7. In a door check, a flat piece of spring metal having one of its ends secured rigidly and the other secured adjustably upon opposite faces of a door, gate, or similar aperture-closing appliance, and having its
60 65

curved center extending around the edge of the same, adapted to engage, by friction and pressure, some fixture, for the purpose of arresting the motion of said door, gate or similar aperture-closing appliance, and having near its adjustable end a projection adapted to be engaged by the human foot or hand to adjust it, substantially as set forth.

8. As an article of manufacture, a flat piece of spring metal bent approximately in a horse-shoe shape, one of its ends adapted to be rigidly and its other end to be secured adjustably upon the opposite faces of a door, a step formed integrally near its adjustable end adapted to be engaged by the human foot, a curved central part adapted to extend around the edge of the door and to adjustably project therefrom, and adapted to engage yieldingly, by pressure, some fixture, as the floor of a room, to arrest the motion of the door, to be used in combination with a raised fixture in the floor near the swing wall of the door and in the path of said spring metal member and adapted to engage said curved central member to prevent the door from swinging from the swing wall, but not projecting high enough to engage the door proper, all substantially as set forth and for the purposes specified.

9. In a door check of the class described, a spring member in the form of an irregular bow adapted to have one of its ends secured adjustably and the other end secured rigidly to opposite faces of the door, in combination with the projecting bow part intermediate said ends, and a hard, thick and smooth surfaced part on said projecting bow adapted to engage by friction some fixture in its path to retard the movement of the door upon which it is secured, substantially as set forth and for the purposes specified.

10. As an article of manufacture, a long flat strip of spring metal bent into the form of an irregular bow, having a short arm, perforated with holes, adapted to receive nails, and having the other extremity or long arm straight, being connected with the former said arm by the connecting convex curve of said bow, and having secured near its adjustable end a step adapted to be engaged by the human foot, and while in its normal assumed shape, the long arm extending inclined toward the extended course of the short arm, said long arm having a longitudinal slot provided with rack teeth, adapted to engage a projecting T-headed pin on one face of a door, substantially as set forth.

11. In a door check of the class described, the combination of a flat spring member having one of its ends secured rigidly and the other end secured adjustably upon opposite faces of a door, gate, or similar aperture-closing appliance, and having its convex curved center extending around the

edge of the same, adapted to engage, by friction and pressure, some fixture, and having near its adjustable end an outward projection adapted to be engaged by the human foot or hand to adjust it, a fixed pin projecting from some fixture adapted to engage a hole in said curved center with a protect-

ing housing inclosing said adjustable end, substantially as set forth.
